GARMENT HANGER

Leonard A. Young, Detroit, Mich., assignor to
 L. A. Young Spring & Wire Corporation, Detroit, Mich.

Application July 28, 1941, Serial No. 404,352

9 Claims. (Cl. 223—92)

This invention relates to improvements in garment hangers.

The main objects of this invention are:

First, to provide an improved satisfactory garment hanger characterized by its rigidity and resistance to distortion or displacement of its parts, notwithstanding the simplicity thereof.

Second, to provide a garment hanger having the above stated advantages which includes a yoke of compressed fibrous stock and a metal suspending hook associated therewith in a novel and highly effective distortion and displacement resistant relation.

Third, to provide a garment hanger suitable for repeated use, and one in which the parts may be economically produced and assembled.

Objects relating to details and economies of the invention will definitely appear from the description to follow. The invention is defined in the claims.

A structure embodying the features of the invention is clearly illustrated in the accompanying drawing in which:

Fig. 1 is a perspective view illustrating a garment hanger in accordance with a preferred embodiment of my invention.

Fig. 2 is an enlarged fragmentary view in section on a line corresponding to line 2—2 of Fig. 1.

Fig. 3 is a fragmentary perspective view of a modified embodiment of my invention, being sectioned vertically to illustrate details of the construction thereof.

Fig. 4 is an enlarged fragmentary view in section on a line corresponding to line 4—4 of Fig. 3.

Fig. 5 is a fragmentary plan view partially broken away and horizontally sectioned to illustrate a further modified embodiment of the invention, and

Fig. 6 is a fragmentary view in section on a line corresponding to line 6—6 of Fig. 5.

This invention relates in general to a garment hanger of the type including a fabricated fibrous garment supporting yoke having a hook operatively associated therewith for suspending garments draped thereon. It is generally similar to the garment hangers shown and described in my copending application for Letters Patent, Serial No. 391,935, filed May 5, 1941.

The present invention is characterized primarily by the simplicity and inexpensiveness of its parts, likewise by the ease with which the parts are operatively assembled, and in assembled condition, by its ruggedness, rigidity and resistance to relative displacement of the parts.

Referring to the drawing, the reference nu-

merals 1 generally designates a garment hanger in accordance with a preferred embodiment of my invention, including a garment supporting yoke 2 of laminated fibrous stock and a suspending hook 3 fabricated of a suitable gauge of wire operatively associated with the yoke.

The yoke 2 is fabricated of a length of a suitable grade of paper or paper board impregnated to stiffen the same if desired. In forming the yoke a web of paper is glued, then passed through a forming die which successfully overlaps the web longitudinally on itself a plurality of times and compresses and conforms the resultant multi-ply web into a T-shape outline or section providing a horizontal top flange 4 of substantial width and a depending relatively thick vertical web 5 located centrally of and beneath the lateral arms 6 of the horizontal flange.

It will be appreciated that flange 4 furnishes an upper garment supporting surface of substantial width and area capable of supporting garments draped thereover without objectionably creasing the same, while the thick depending web 5 greatly strengthens and rigidifies the yoke as a whole and resists bending, twisting or like distortion thereof. In order to secure the hook 3 to the yoke centrally thereof, I form the lower end of the shank 7 of the hook, as clearly illustrated in Fig. 2, to provide a laterally offset horizontal bight 8, the horizontal arms 9 of which are clampingly, and preferably embeddingly engaged with the flange 4 at one side thereof. The lower arm 9 is offset 90 degrees downwardly and conformed in an upwardly facing bight 10, the arms 11 of which are grippingly, and preferably embeddingly, engaged with the web 5. This results in a strong clamping and binding engagement of the hook with the yoke which is very simply produced and very effectively resists separation of the parts.

In Figs. 3 and 4 I illustrate a structure which is generally similar to that shown in Fig. 1, save that the hook 12 is formed of a pair of integrally connected wire strands 13 folded 180 degrees into parallel and in side by side relation to one another, these strands being twisted at 14 to form the shank of the hook.

At the lower end of the shank the strands 14 are conformed in the same manner as is the single wire shank 7 shown in Figs. 1 and 2, but face oppositely; hence I have designated the various parts by similar reference numerals, it being understood that the respective strands engage the opposite sides of the yoke as shown and de-

scribed, constituting a highly effective distortion and displacement resistant structure.

In Figs. 5 and 6 I illustrate a still further embodiment of the invention wherein a shank 15 having the twisted strands 16 is employed. In this case the strands are laterally offset in opposite directions at 17 and provided with bights 18 grippingly engaging the top flange arms of the yoke. The extremities of the bights 18 are again offset in opposite directions parallel to the yoke and are grippingly and preferably embeddingly engaged with the web 5 thereof immediately beneath flange 4. To improve the effectiveness of the gripping engagement, the extremities are given a corrugated or wavy outline at 19 enabling the same to be readily indented into the stock of the web.

In assembling the foregoing structure the yoke and hook are brought together in an automatic machine which crimps or folds the hook extremity about the flange and web of the yoke in the manner described above, resulting in a very firm displacement-resistant structure. These hangers are very strong and rigid, and may be used repeatedly without becoming inoperative due to separation or breakage of the parts.

Embodiments of the invention which incorporate the principles of the invention in a highly desirable manner have been illustrated and described. It should be understood that the foregoing terminology is used descriptively rather than in a limiting sense, and with full intention to include equivalents of the features shown and described, within the scope of the following claims.

Having thus described my invention what I claim as new and desire to secure by Letters Patent is:

1. A garment hanger comprising a garment supporting yoke fabricated of multi-ply paper stock folded a plurality of times upon itself and conformed to a T-shaped section providing a top garment supporting flange of substantial width and area and a bottom reinforcing web of substantial thickness depending centrally from said flange, and a wire hook having a laterally extending bight adjacent its lower end grippingly engaged with the top and bottom sides of said flange, one arm of said bight being offset downwardly and terminating in a further upwardly opening bight grippingly engaged with either side of said web whereby said hook and yoke are maintained from relative displacement.

2. A garment hanger comprising a garment supporting yoke fabricated of multi-ply paper stock folded a plurality of times upon itself and conformed to a section providing a top garment supporting flange of substantial width and area and a bottom reinforcing web of substantial thickness depending from said flange, and a wire hook having a laterally extending bight grippingly engaged with the top and bottom sides of said flange and a further upwardly opening bight grippingly engaged with either side of said web whereby said hook and yoke are maintained from relative displacement.

3. A garment hanger comprising a garment supporting yoke conformed to provide a top horizontal garment supporting flange of substantial

width and area and a reinforcing web depending from said flange, and a suspending hook having a bight grippingly engaged with said flange and a second bight clampingly engaged with said web, whereby said hook and yoke are maintained from relative displacement.

4. A garment hanger comprising a yoke of fibrous stock folded in multi-layer T-shaped outline to provide a top horizontal garment supporting flange of substantial width and a vertical reinforcing web of substantial thickness depending from said flange to reinforce the yoke, and a wire hook associated with said yoke provided with a bight grippingly engaged with said flange, said hook terminating in fingers offset parallel to the yoke engaged with the web thereof, whereby relative movement of the yoke and hook is prevented.

5. A garment hanger comprising a yoke of T section providing a top horizontal garment supporting member of substantial width and a vertical reinforcing web element of substantial thickness depending from said top member to reinforce the yoke, and a wire hook associated with said yoke provided with an intermediate portion engaged with said top member and a terminal portion grippingly engaged with the bottom of the web element, whereby relative movement of the yoke and web is prevented.

6. A garment hanger comprising a yoke of T section fabricated of paper stock providing a top garment supporting portion of substantial width and a vertical midrib of substantial thickness, and a wire suspending hook provided with a shank terminating in an upwardly facing loop clampingly embracing said midrib and provided with a laterally facing loop clampingly embracing one edge of said top portion.

7. A garment hanger comprising a yoke of T section fabricated of multi-ply paper stock providing a top garment supporting portion of substantial width and a vertical reinforcing web, and a wire suspending hook formed of a piece of wire folded upon itself, the resulting strands being disposed side by side and twisted together to provide a shank, the strands terminating in oppositely disposed upwardly facing loops grippingly embracing said web and loops grippingly engaging the top portion of said yoke.

8. A garment hanger comprising a yoke of T section fabricated of paper stock providing a top garment supporting portion of substantial width and a vertical reinforcing web, and a suspending hook comprising wire strands twisted together to provide a shank, the strands having oppositely disposed loops below such twists, the loops grippingly embracing the edges of said top portion of said yoke, the free arms of the loop terminating in portions disposed longitudinally of and in gripping engagement with the sides of the web.

9. A garment hanger comprising a yoke of T section fabricated of paper stock providing a top garment supporting portion of substantial width and a vertical reinforcing web, and a suspending hook comprising wire strands twisted together to provide a shank, the strands having oppositely disposed loops below such twists, the loops grippingly embracing the edges of said top portion of said yoke.
